Primary Examiner — Garth Rademaker*Assistant Examiner* — Melvin L Davis(74) *Attorney, Agent, or Firm* — Dunlap Bennett & Ludwig PLLC; Brendan E. Squire(57) **CLAIM**

The ornamental design for a flotation ring, as shown and described.

DESCRIPTION

FIG. 1 is a front perspective view of the flotation ring showing my new design;

FIG. 2 is a front elevation view thereof, the rear elevation view being an identical image thereof;

FIG. 3 is a left side elevation view thereof, the right side elevation view being an identical image thereof;

FIG. 4 is a top plan view thereof; and,

FIG. 5 is a bottom plan view thereof.

The broken lines shown in the drawings illustrate portions of the flotation ring that form no part of the claimed design.
